MAP HOLDER

Richard H. Winslow and Harold E. Marsh,
Reseda, Calif.

Application June 19, 1950, Serial No. 10,632

Term of patent 14 years

(CL. D14—6)

To all whom it may concern:

Be it known that we, Richard H. Winslow and Harold E. Marsh, citizens of the United States, residing at Reseda, California, have invented a new, original, and ornamental Design for a Map Holder, of which the following is a specification, reference being had to the accompanying drawing, forming part thereof:

Fig. 1 is a perspective view taken from the front of the map holder, showing a new design.

Fig. 2 is a rear elevational view.

Fig. 3 is a side elevational view taken from the right hand side of Fig. 2.

Fig. 4 is a bottom view with a portion of the device broken away for convenience of illustration.

Fig. 5 is a side elevational view taken from the left hand side of the map holder as viewed in Fig. 2.

We claim:

The ornamental design for a map holder, as shown.

RICHARD H. WINSLOW.
HAROLD E. MARSH.
